Filed May 1, 1968, Ser. No. 11,725

Term of patent 14 years

Int. Cl. D21—01

U.S. Cl. D34—13

FIGURE 1 is a perspective view of a duplicate bridge board or similar article embodying my new design;

FIGURE 2 is a perspective view thereof shown in open position;

FIGURE 3 is a side elevational view thereof taken from the side opposite that visible in FIG. 1; and

FIGURE 4 is an end elevational view thereof taken from the end opposite that visible in FIG. 1.

The bottom of the board shown in FIG. 1 is substantially the mirror image of the top. The broken-line showing of playing cards and data cards is for purposes of illustration only.

I claim:

The ornamental design for a duplicate bridge board or similar article, substantially as shown and described.
